UNITED STATES PATENT OFFICE.

WILLIAM HOUSTON, OF HAVERHILL, MASSACHUSETTS.

PIE-PLATE ATTACHMENT.

Application filed February 24, 1928. Serial No. 256,560.

This invention relates to pie plate attachments of the type shown in my Patent #1,640,409, in which a detachable ring is provided which is adapted to be set in position 5 on the plate rim, so that the pie crust may be built up against it, and will be retained in the built up position thereby until after the pie has been baked, after which the ring may be removed.

10 While the construction of my said prior patent will serve the purpose for which it is intended, it has several objectionable features which it is the purpose of the present invention to overcome, the more important of 15 which are the high cost of manufacture, the difficulty of cleaning after use and the liability of distortion from use.

The object of the present invention therefore is to provide a device of the above described type which may be manufactured at greatly reduced expense, as compared with prior devices for the purpose, which may be readily cleaned after use and which will be sufficiently rigid to prevent distortion from 25 ordinary use.

For a more complete disclosure of my invention, reference is made to the following specification, in connection with the accompanying drawings, in which:

30 Fig. 1 is a plan view of a preferred embodiment of my invention.

Figs. 2, 4 and 5 are detail sectional views at the lines 2—2, 4—4, and 5—5 respectively of Fig. 1 and

35 Fig. 3 is a detail side view of a section of the attachment.

According to my present invention I provide a strip of thin sheet metal of suitable width, which is adapted to be molded transversely by being passed between die rolls, similar to the ordinary crimping rolls in general use. Said strip is shaped to provide a heavily fluted edge portion *a*, the flutes in which taper to an intermediate, or base portion *b*, which is located approximately in the plane of the ring, and a depending edge flange *c*, or cylindrical portion, which extends from the base portion oppositely with relation to the fluted portion and approximately perpendicularly to the base portion, but preferably so that the internal angle between the base and flange is slightly obtuse, or so that the latter flares slightly with relation thereto. The formation of the fluted portion *a* is such that each external concavity tapers in depth from the edge of the fluted portion to

the base, so that what may be considered as the middle portion of the bottom of each external concavity extends obliquely inward from the base portion, the depth thereof thus increasing from a maximum at the edge to nothing at the base. The middle of the bottom of each internal concavity extends approximately perpendicularly to the base, the maximum depth of the internal concavities 65 also being at the edge and tapering down to nothing at the base.

In constructing the attachments, strips of metal are passed between moulding rolls so that they are shaped transversely in the 70 form above described. The molded strips are then cut into suitable lengths and each section thus formed is bent into circular form and its end portions are overlapped to an extent to produce a ring of the desired internal diameter, so that the inner surface of the 75 overlapping portion fits against the corresponding portions of the outer surface of the overlapped portion, as shown in Fig. 5, said portions being secured together at two points 80 by rivets, as *d*, or by any other suitable means, as solder. The lapped portions, as thus secured will effectively resist lateral distortion by reason of their intimate engagement at different angles. Also the angularly disposed base and flange portions effectively act to stiffen the ring and hold it in circular form.

The manner of using the device is identical with that disclosed in my said prior patent and is indicated in Fig. 2, as it will be placed 90 on the rim of a plate, as *e*, so that the base portion *b* rests on the top side thereof and the flange *c* encloses its edge, after which the dough may be built up against the fluted portion.

95 After the baking operation, the ring may be readily lifted upward, and as all the surfaces above the base *b* incline inward from the base, except the middle line of the internal flutes, which may be approximately perpendicular, as shown. The crust usually shrinks slightly in baking so that ready removal is permitted.

100 The above described construction may be produced at small expense, as the forming operation, by passing between molding rolls, may be rapidly performed, while the subsequent step of cutting the strip into suitable lengths, lapping the ends and connecting them, may be easily performed, so the total 110 cost of production will be less than half of that of my prior constructions.

I claim:

1. A pie plate attachment comprising a ring composed of a continuous strip of sheet metal bent into circular form and having its ends joined, said ring having one edge portion of slightly greater internal diameter than the diameter of the edge of the plate rim, to permit the same to be removably fitted thereon from the top side, and an intermediate portion, adapted to engage the top side of the rim to support the ring on the plate, the opposite edge portion of said ring being fluted and the flutes thereof being tapered in depth from the edge to said intermediate portion.
2. A pie plate attachment comprising a ring composed of a continuous strip of sheet metal having its ends joined, said ring having one edge portion cylindrically shaped and of slightly greater internal diameter than the diameter of the edge of the plate rim, to permit the same to be removably fitted thereon, and an inwardly extending intermediate portion adapted to rest on the top side of the rim, the opposite edge-portions of the ring being fluted and the bottoms of the external cavities thereof being inclined inward from said intermediate portion and said cavities increasing in depth from said intermediate portion to the edge.

tion adapted to rest on the top side of the rim, the opposite edge-portion of the ring being fluted and the flutes thereof being tapered in depth as they extend from the edge to the inner portion of said intermediate portion.

3. A pie plate attachment comprising a ring composed of a continuous strip of sheet metal having its ends joined, said ring having one edge portion cylindrically shaped and of slightly greater internal diameter than the diameter of the edge of the plate rim, to permit the same to be removably fitted thereon, and an inwardly extending intermediate portion adapted to rest on the top side of the rim, the opposite edge-portions of the ring being fluted and the bottoms of the external cavities thereof being inclined inward from said intermediate portion and said cavities increasing in depth from said intermediate portion to the edge.

In testimony whereof, I have signed my name to this specification.

WILLIAM HOUSTON.
